2 SHEETS-SHEET 2.

UNITED STATES PATENT OFFICE.

WILLIAM J. KLEMM, OF KANSAS CITY, MISSOURI.

PANEL CONSTRUCTION.

986,013.

Specification of Letters Patent. Patented Mar. 7, 1911.

Application filed October 4, 1910. Serial No. 585,220.

To all whom it may concern:

Be it known that I, WILLIAM J KLEMM, a citizen of the United States, residing at Kansas City, in the county of Jackson and 5 State of Missouri, have invented certain new and useful Improvements in Panel Construction, of which the following is a specification.

My invention relates to improvements in 10 panel construction.

The object of my invention is to provide a panel construction possessing the features of simplicity, durability and efficiency, and which is particularly adapted to the em- 15 ployment of sheet metal in its composition.

The novel features of my invention are hereinafter fully described and claimed.

In the accompanying drawings which represent the preferred form of my invention, 20 I have illustrated my improvement as applied to a sheet metal door.

Figure 1 is an elevation of the door portions of which are broken away. Fig. 2 is an enlarged view partly in elevation and 25 partly in vertical section of a portion of the door shown in Fig. 1. Fig. 3 is a sectional view, enlarged, on the dotted line *a*—*b* of Fig. 1. Fig. 4 is an enlarged sectional view on the dotted line *c*—*d* of Fig. 1. Fig. 5 is a cross section on the dotted line *e*—*f* of 30 Fig. 2. Fig. 6 is a stretchout of one end of the top rail. Fig. 7 is a stretchout of one end of one of the middle rail members. Fig. 8 is an end view of the top rail. Fig. 9 is 35 a sectional view on the dotted line *g*—*h* of Fig. 1. Fig. 10 is a vertical section on the dotted line *i*—*j* of Fig. 1.

Similar reference characters denote similar parts.

1 denotes the stiles of the door. Each stile 1 is provided with two longitudinal transversely disposed portions 2 which extend toward each other at the panel side of the stile, said portions having vertical lat- 45 erally extending parallel flanges 3.

4 denotes a clamping member, which like the stile 1, is preferably composed of sheet metal. The clamping member 4 is preferably in the form of a rectangular tube and 50 is disposed vertically in the stile 1 and has one side resting against the inner sides of the portions 2. Said side of the clamping member 4 is provided with two longitudinal laterally extending parallel portions 5 be- 55 tween which is clamped a panel 6 of any desired material or construction. The outer

edges of the portions 5 have return bends 7 between which are respectively clamped the flanges 3 of the stile 1. The return bend portions 7 are provided with vertical flanges 8 disposed adjacent to and parallel with the portions 2 respectively of the stile 1. Each flange 8 is preferably resilient and is also preferably provided with a longitudinal corrugation 9 adapted to engage a similar 65 corrugation 10 of a vertical flange 11 of a rail or molding. 12 denotes rivets or other suitable securing devices which extend through holes provided transversely in the panel 6, portions 5, flanges 3 and return 70 bend portions 7.

The top rail denoted by 13 has a body preferably formed U shaped and provided at its lower horizontal edges with inwardly extending portions 2 having flanges 3 cor- 75 responding to the similar parts on the stile 1 already described. Each end of the rail 13 is provided with two vertical flanges 11 having each a vertical corrugation 10 adapt- 80 ed to fit the adjacent corrugation 9 of the 85 adjacent flange 8, as shown in Fig. 3.

The lower rail denoted by 14 may be constructed in substantially the same manner as is the top rail 13.

The middle rail 15 may be composed of 85 two members, each having at its upper and lower edges the portions 2 and flanges 3. In the middle rail 15 are mounted two horizontal clamping members 4 disposed one above the other and provided each with the 90 portions 5, and return bend portions 7 hav- 95 ing flanges 8 provided with the corrugations 9, all of which have been fully described. Each member of the middle panel 15 is pro- 100 vided with the flanges 11 having corruga- 105 tions 10 adapted to engage the corrugations 9 of the flanges 8 on the stiles 1, in the same manner as has been described with reference to the corresponding flanges 11 of the top rail 13.

The top rail 13 and the bottom rail 14 have mounted in them respectively two horizontal clamping members 4 having the parallel portions 5, with return bend portions 7 for engaging the flanges 3 of the said rails. 105 The return bend portions 7 of the said clamping members are provided with flanges 8 having corrugations 9 for engaging horizontal moldings 16 provided with flanges 11 having corrugations 10 which engage the 110 corrugations of the flanges 8 of said rails. In like manner horizontal moldings 16 at

opposite sides of the panel 6, have corrugated flanges 11 which engage the corrugated flanges 8 of the two members of the middle rail 15, as shown in Fig. 9. Vertical moldings 16 at opposite sides of the panel 6 have vertical flanges 11 having corrugations 10 for engaging the corrugated flanges 8 of the vertical clamping members 4 in the stiles 1.

10 In assembling the parts, the vertical clamping members 4 are slipped endwise into engagement with the portions 2 and flanges 3 of the stiles 1. In like manner the clamping members 4 are slipped into the rails 13, 14 and 15. The top rail 13 is then slipped vertically with its flanges 11 engaging the flanges 8 of the stile clamping members 4. The top panel 6 is then slipped between the portions 5 of the stile clamping members to a position in which its upper end will enter the space between the horizontal portions 5 of the clamping member 4 in the top rail. The middle rail 15 is then slipped into position from the bottom of the door and between the vertical portions 5 of the stile clamping members. When properly positioned the upper panel 6 will enter the space between the horizontal portion 5 of the upper middle rail clamping member.

15 30 The lower panel is then slipped into position in the same manner, after which the bottom rail 14 is slipped into position by moving it vertically between the portions 2 of the stile clamping members 4. The rivets 12 are then secured in position, thereby holding the parts so far assembled in their respective positions. The moldings 16 are then positioned by forcing them horizontally against the panels 6, the flanges 11 spring-

20 35 40 45 50 55 60 65 70 75 80 85 90 95 100 105 110 115 120 125 130

ing the resilient flanges 8 sufficiently for the corrugations 10 to enter and engage with the corrugations 9 of the flanges 8, thus causing the moldings to be securely held, the flanges 8 springing to their normal positions as soon as the moldings 16 have been forced to their proper positions. If desired the rails 13 and 14 may be braced by positioning therein and securing thereto horizontal U shaped bars 17, as shown in Figs. 2, 4 and 10.

I do not limit my invention to the structure shown and described, as many modifications, within the scope of the appended claims, may be made without departing from the spirit of my invention.

While I have shown my invention applied to door construction, it will be obvious that it may be applied with equal benefit to window construction and to the construction of partitions and similar structures.

Having thus described my invention, what I claim and desire to secure by Letters Patent, is:—

65 1. In panel construction, a stile or rail

having at one side two longitudinal transversely disposed portions having laterally extending flanges disposed parallel with each other, a longitudinal clamping member having one side resting against the inner 70 sides of said transversely disposed portions, said side having two laterally extending parallel portions resting respectively against the said flanges and adapted to clamp between them a panel, and means for securing 75 said laterally extending parallel portions to said flanges respectively.

2. In panel construction, a stile or rail having at one side two longitudinal transversely disposed portions having laterally 80 extending flanges disposed parallel with each other, and a longitudinal clamping member having one side resting against the inner sides of said transversely disposed portions, said side having two laterally extending parallel portions the outer edges of which are provided with return bends between which said flanges are clamped.

3. In panel construction, a stile or rail having at one side two longitudinal transversely disposed portions having laterally extending parallel flanges, and a longitudinal clamping member having one side resting against the inner sides of said transversely disposed portions, said side having 90 two laterally extending parallel portions the outer edges of which are provided with return bends between which said flanges are respectively clamped, said return bends having longitudinal flanges disposed parallel 95 with and adjacent to said transversely disposed portions respectively.

4. In panel construction, a stile or rail having at one side two longitudinal transversely disposed portions having laterally 105 extending parallel flanges, and a longitudinal clamping member having one side resting against the inner sides of said transversely extending portions, said side of the clamping member having two laterally extending parallel portions the outer edges of which are provided with return bends between which said flanges are respectively clamped, the return bends having longitudinal resilient flanges disposed parallel with and adjacent to said transversely disposed portions respectively.

5. In panel construction, a stile or rail having at one side two longitudinal transversely disposed portions having laterally 120 extending parallel flanges, and a longitudinal clamping member having one side resting against the inner sides of said transverse portions, said side of the clamping member having two laterally extending parallel portions the outer edges of which are provided with return bends between which said flanges are respectively clamped, the return bends having respectively longitudinal corrugated flanges disposed parallel 125 130

with and adjacent to said transversely disposed portions respectively.

6. In panel construction, a stile or rail having at one side two longitudinal transversely disposed portions having laterally extending parallel flanges, and a longitudinal clamping member having one side resting against the inner sides of said transversely disposed portions, said side of said 10 clamping member having two laterally extending parallel portions the outer edges of which have return bends between which the flanges are respectively clamped, the return bends having respectively longitudinal corrugated resilient flanges disposed parallel with and adjacent to said transversely disposed portions respectively.

7. In panel construction, a stile or rail having at one side two longitudinal transversely disposed portions having laterally extending flanges disposed parallel with each other, a longitudinal clamping member having one side resting against the inner sides of said transversely disposed portions, said side of the clamping member having two laterally extending parallel portions; a panel clamped between said laterally extending parallel portions, and means for securing the panel to said laterally extending portions and said laterally extending portions to said flanges.

8. In panel construction, a stile or rail having at one side two longitudinal transversely disposed portions having laterally extending parallel flanges; a longitudinal clamping member having one side resting against the inner sides of said transversely disposed portions, said side of the clamping member having two laterally extending 40 parallel portions, a panel clamped by said laterally extending parallel portions, and rivets or similar securing devices extending through said panel, said flanges and said laterally extending parallel portions.

- 45 9. In panel construction, a stile or rail having at one side two longitudinal transversely disposed portions having laterally extending parallel flanges, a longitudinal clamping member having two laterally extending parallel portions the outer edges of which have return bends between which are clamped the said flanges respectively, a panel clamped between said laterally extending parallel portions, and means for 55 securing the panel to said laterally extending parallel portions.

10. In panel construction, a stile or rail having at one side two longitudinal transversely disposed portions having laterally 60 extending parallel flanges, a longitudinal clamping member having two laterally extending parallel portions the outer edges of which have return bends between which the said flanges are respectively clamped, said 65 return bends having respectively longitudi-

nal corrugated flanges disposed parallel with and adjacent to said transversely disposed portions respectively, and a member such as a rail or molding having a corrugated flange adapted to be held between one of 70 said corrugated flanges and the adjacent transversely disposed portion of the stile and having its corrugation engaging the corrugation of the adjacent corrugated flange of the clamping member.

75 11. In panel construction, a stile or rail having at one side two longitudinal transversely disposed portions having laterally extending parallel flanges, a longitudinal clamping member having two laterally extending parallel portions the outer edges of which have return bends between which the flanges are respectively clamped, said return bends having respectively longitudinal corrugated resilient flanges disposed parallel 80 with and adjacent to said transversely disposed portions respectively, and a member, such as a rail or molding having a corrugated flange adapted to be inserted between one of said corrugated flanges and the adjacent transversely disposed parallel portion 85 of the stile, with its corrugation engaging the corrugation of the adjacent corrugated flange of the clamping member.

90 12. In panel construction, a stile or rail having at one side two longitudinal transversely disposed portions having laterally extending parallel flanges, a longitudinal clamping member having two laterally extending parallel portions the outer edges of 100 which have return bends between which said flanges are respectively clamped, said return bends having respectively two longitudinal corrugated flanges disposed parallel with and adjacent to said transversely disposed 105 portions respectively, and a member, such as a rail having two corrugated flanges for respectively engaging the corrugated flanges of the clamping member and said transversely disposed portions of the stile.

110 13. In panel construction, a stile or rail having at one side two longitudinal transversely disposed portions having laterally extending parallel flanges, a longitudinal clamping member having two laterally extending parallel portions the outer edges of which have return bends having each a longitudinal corrugated flange, a panel disposed between said laterally extending parallel portions of the clamping member, and 115 a member, such as a rail having two corrugated flanges respectively engaging the corrugated flanges of the clamping member and said transversely disposed portions of the stile.

120 14. In panel construction, a stile or rail having at one side two longitudinal transversely disposed portions having laterally extending parallel flanges, a longitudinal clamping member having two laterally ex- 125

tending parallel portions the outer edges of which have return bends having each a longitudinal corrugated flange, a panel between said laterally extending parallel portions, securing devices extending through the panel and said laterally extending portions, and a member, such as a rail, having two corrugated flanges respectively engaging the corrugated flanges of the clamping member

and the transversely disposed portions of 10 the stile.

In testimony whereof I have signed my name to this specification in presence of two subscribing witnesses.

WILLIAM J. KLEMM.
